COMBINED TAILPIECE AND BRIDGE FOR A
GUITAR OR SIMILAR ARTICLE

Stanley E. Rendell, Kalamazoo, Mich., assignor to Chicago Musical Instrument Co., Lincolnwood, Ill.

Filed June 22, 1971, Ser. No. 155,683

Term of patent 14 years

Int. Cl. D17—03
U.S. Cl. D56—1 A

FIG. 1 is a top plan view of a combined tailpiece and bridge for a guitar or similar article, showing my new design;

FIG. 2 is an upper edge elevational view;

FIG. 3 is a lower edge elevational view;

FIG. 4 is a left edge elevational view; and

FIG. 5 is a right edge elevational view thereof.

The back, not shown, is plain and unornamented.

I claim:

The ornamental design for a combined tailpiece and bridge for a guitar or similar article, substantially as shown and described.
